UNITED STATES PATENT OFFICE.

JOSEPH BERGE, OF FLINT, MICHIGAN, ASSIGNOR TO CHAMPION IGNITION COMPANY, OF FLINT, MICHIGAN, A CORPORATION OF MICHIGAN.

DESIGN FOR A SPEEDOMETER FACE-PLATE.

53,217.

Specification for Design.

Patented Apr. 22, 1919.

Application filed January 6, 1919. Serial No. 269,950. Term of patent 14 years.

To all whom it may concern:

Be it known that I, JOSEPH BERGE, a citizen of the United States, residing at Flint, in the county of Genesee and State of Michigan, have invented a new, original, and ornamental Design for Speedometer Face-Plates, of which the following is a specification, reference being had to the accompanying drawing, forming part thereof.

The figure is a front elevation of a face plate for speedometers showing my new design.

I claim:

The ornamental design for a speedometer face plate, as shown.

In testimony whereof, I hereunto affix my signature.

JOSEPH BERGE
